United States Patent Office

Des. 203,807
Patented Feb. 22, 1966

203,807

ELBOW MACARONI

Joseph Pellegrino, 10 Sherbourne St., Andover, Mass.

Filed Mar. 1, 1963, Ser. No. 73,784

Term of patent 14 years

(Cl. D8—1)

Fig. 1.

Fig. 2.

Fig. 3.

I claim:

The ornamental design for an elbow macaroni, substantially as shown.
